PROCESS FOR LINING SHAFTS

Carl-Sonderegger, Zurich, Switzerland, assignor to Electro-Watt Electrical and Industrial Management Co., Ltd., Zurich, Switzerland, a company of Switzerland

Application December 24, 1947, Serial No. 793,702
In Switzerland December 21, 1946

Section 1, Public Law 690, August 8, 1946
Patent expires December 21, 1966

4 Claims. (Cl. 61—41)

1

Pressure shafts are generally made nowadays by introducing sections of steel piping of fixed length into excavated shaft and joined together. After being placed in position these lengths or sections of steel piping are backed with concrete to give them a bearing on the rock. The pipes must be of such dimensions that they withstand any pressure likely to be exerted either from inside or outside, and therefore have walls of substantial thickness. Quite apart from the complications involved in laying of the extremely heavy lengths of piping, this method of construction is also extremely expensive and the backing with concrete is a difficult process.

The present invention relates to a process for the production of pressure shafts with which process only armouring of minimum wall-thickness is necessary, which process is considerably simpler and cheaper than the method of construction described above. The process for the manufacture of armoured pressure shaft linings in excavated shafts is characterized by the fact that first of all a layer of concrete is applied on which thin sheet metal armouring consisting in the longitudinal direction of individual sections, open at one side and joined, after laying, to form a continuous pipe, is arranged in such a way that between the layer of cement bearing against the rock and the sheet itself a space of several millimetres is left, a further layer of cement being then applied to the sheet armouring, the space between the outer layer of concrete and the sheet armouring being finally filled with cement grout under the highest pressure which the inner concrete lining can withstand, in order to ensure snug fitting of the sheet.

The pressure shaft produced by this process is characterized by an outer layer of concrete bearing against the rock, a further, inner concrete lining and a thin sheet armouring between these layers of concrete, the sheet armouring lying directly on the inner concrete lining, whilst between the sheet armouring and the outer layer of concrete a subsequently applied thin layer of concrete, is provided.

The sheet armouring, which is roughly 2 mm. in wall thickness, may be introduced into the shaft, which is already provided with the outer layer of cement, in lengths of 4-6 metres, the individual lengths being then welded together in the pressure shaft. To the longitudinal sections of sheet armouring sheet metal strips of thicker gauge than the armouring are expediently welded before the sections are introduced into the pressure shaft, these strips then being joined

2

together by fillet welding. The strength of the welded joints can thereby be made to equal that of the sheet. For transverse sections, however, it is sufficient if fillet welding is carried out over the thickness of the sheet.

It is possible, however, to dispense with welding the individual lengths together by making both the longitudinal and transverse sections overlapping and inserting a wire mesh between the overlapping parts. By selecting the amount of overlap the cement grout penetrating into the overlap can be made to take the full strain of the sheet after the cement has set hard. Between the sheet armouring and the outer cement ring a space must be left, as already stated, this space being then filled with cement grout introduced under pressure. This cavity can be produced by fastening a spot-welded wire mesh to the outer layer of concrete before the sheet sections are introduced. This wire mesh ensures that a space is left between the sheet armouring and the outer layer of concrete and enables the cement grout introduced under pressure completely to fill the intermediate space. Alternatively, ribs or grooves may be provided on the outer concrete layer at the time said layer is produced, though these would have to be fashioned in such a way as to enable the cement grout to penetrate in every direction. In view of the fact that the cement grout is injected under high pressure the sheet jacket will certainly be moved slightly, so that an intermediate layer, thin though it may be, can be produced, even at those points where ribs are provided, by the injected cement grout.

In the enclosed drawing Figs. 1-4 show several typical embodiments of the invention, and represent:

Fig. 1 a section showing the structure of the pressure shaft;

Fig. 2 the joining of the longitudinal sections of the individual pipes;

Fig. 3 the joining of the lengths of piping by the insertion of a wire mesh;

Fig. 4 a section of the structure of a pressure shaft, ribs being provided, on the outer ring of concrete, between said outer ring of concrete and the sheet armouring.

In Fig. 1, 1 designates the rock face of the excavated shaft on which rock face a layer of concrete 2 is first laid. A wire mesh 3 is secured to this layer of concrete, after which the sheet metal jacket 4 is placed in position. Said sheet metal jacket is joined, as shown in Fig. 2, by a fillet welding 5, plates 6 and 7, which are con-

siderably thicker than the sheet metal jacket 4 itself, being welded to the sheet metal jacket 4, which is only about 2 mm. thick. In this way it is possible to arrange for the strength of the welded joint to be equal to that of the sheet metal jacket. After the sheet metal jacket 4 has been placed in position, a further layer of concrete 8 is applied, which may for example be reinforced with iron 9. Cement grout is injected between the sheet metal jacket 4 and the layer of concrete 2 under the highest pressure that the layer of concrete 8 is capable of withstanding, whereby the sheet metal jacket 4 is pressed against the inner ring of concrete and an intimate union between all the layers is created. 15

In the case of the embodiment according to Fig. 3 a wire mesh 3 is inserted in the overlap of the individual sections. In the course of filling up the space between the layer of concrete 2 and the sheet metal jacket 4 of the cement grout will also penetrate into the overlap of the pipe sections and, after the cement has set, form a joint. The overlap can be of such dimensions that the strength of the joint is, with absolute certainty, equal to that of the sheet metal armouring. 20

Finally Fig. 4 shows how, instead of the wire mesh 3, grooves 10 are provided on the outer layer of concrete 2. As already mentioned, the high pressure under which the cement grout is injected will tend to move the sheet metal jacket 4 slightly, so that a layer of cement is formed even underneath the bearing surfaces between the grooves. 30

As has been shown by the above explanation, it is possible with the process according to the invention to make, with extremely simple means and at low cost, pressure shafts which are absolutely tight and are at the same time capable of withstanding all pressures which may arise either from inside or outside. 35

I claim:

1. A process for making armoured pressure shaft linings comprising the steps of applying an outer layer of concrete to the shaft, placing an armouring member of thin sheet metal and overlapping longitudinal edges in spaced relationship with the outer layer of concrete, securing together the overlapping edges of the armouring member, applying an inner layer of concrete to the inner surface of the armouring member, and filling the space between the outer layer of concrete and the armouring member with cement grout under pressure limited by the strength of the inner concrete layer. 45

2. A process for making armoured pressure shaft linings comprising the steps of applying an outer layer of concrete to the surface of the shaft, placing a wire mesh against the surface of the outer concrete layer, placing one imperforate armouring member with overlapping longitudinal edges and open ends in the shaft and adjacent the wire mesh, placing another imperforate armouring member with overlapping longitudinal 55

edges and open ends in the shaft with one end in abutted relationship with an end of the first armouring member, securing together the overlapping longitudinal edges of each member, placing reinforcement members adjacent the inner surface of each member, applying an inner layer of concrete over the reinforcement members and against the inner surfaces of the armouring members, and introducing cement grout under pressure into the space occupied by the wire mesh. 10

3. A process for making armoured pressure shaft linings comprising the steps of applying an outer concrete layer to the shaft, placing an armouring member of thin sheet metal and overlapping longitudinal edges and open ends in the shaft adjacent the outer concrete layer, placing a second armouring member of thin sheet metal and overlapping longitudinal edges and open ends in the shaft adjacent the outer concrete layer with one end of the second member overlapping the corresponding end of the first member, securing together the overlapping portions of the members, applying an inner layer of reinforced concrete to the inner surface of the armouring members, and introducing cement grout under a pressure of less than the fracturing pressure of the inner concrete layer intermediate the outer concrete layer and the armouring members. 20

4. A process for making armoured pressure shaft linings comprising the steps of applying an outer concrete layer to the shaft, forming interconnecting grooves on the surface of the outer concrete layer, placing an armouring member of thin sheet metal and overlapping longitudinal edges and open ends in the shaft against the outer concrete layer, placing a second armouring member of thin sheet metal and overlapping longitudinal edges and open ends in the shaft against the concrete layer with one end of the second member overlapping the corresponding end of the first member, placing a wire mesh between the overlapping edges of each member, placing an inner layer of reinforced concrete against the inner surface of the armouring member, and introducing cement grout under a pressure less than the fracturing pressure for the inner reinforced concrete layer intermediate the outer concrete layer and armouring members. 40
